UNITED STATES PATENT OFFICE.

GRANVILLE G. WESTERFIELD, OF INDIANAPOLIS, INDIANA.

INTERNAL-COMBUSTION ENGINE.

1,421,878.

Specification of Letters Patent. Patented July 4, 1922.

Application filed April 19, 1920. Serial No. 374,934.

To all whom it may concern:

Be it known that I, GRANVILLE G. WESTERFIELD, a citizen of the United States, residing at Indianapolis, in the county of Marion 5 and State of Indiana, have invented a new and useful Internal-Combustion Engine, of which the following is a specification.

It is the object of my invention to vary the compression space of an internal combustion engine to suit different fuels and different conditions of operation, by varying the position of the piston at the end of the compression stroke as desired; and to produce a power stroke which is longer than 10 the intake stroke so that at the ends of the power strokes a supplemental exhaust port in the cylinder wall is uncovered to permit the burned gases to escape after substantially the full energy from their expansion 15 has been obtained and to improve the scavenging, and to obviate the necessity for opening the main exhaust valve while it is under pressure and before the entire energy from the expanding gases has been obtained.

20 In attaining this object, instead of connecting the connecting rod of each piston directly to a crank pin having a simple circular motion as in the ordinary engine, I connect it to an eccentric (or crank pin) on 25 the main crank pin, which eccentric in addition to the circular motion about the axis of the crank shaft also has a superposed circular motion about the axis of the main crank pin, the superposed motion in the preferred form of my invention having half the 30 angular velocity of the main crank pin. By maintaining the proper relation between the two motions, the piston is made to move further toward the crank shaft on the power 35 strokes than on the intake strokes, by twice the distance by which the eccentric is offset from the axis of the crank pin, but the piston is brought to the same or nearly the same position at the ends of the compression and 40 exhaust strokes. In addition, by shifting the angle at which the eccentric is offset from the axis of the main crank pin for a given position of the latter, which shifting I provide means for obtaining, the position 45 of the piston in the cylinder at the ends of the compression and exhaust strokes may be varied as desired, thus controlling the size 50 of the compression space, without materially varying the positions which the piston takes 55 at the ends of the power and intake strokes.

The accompanying drawings illustrate my

invention. Fig. 1 is a simple diagrammatic plan of a four-cylinder engine embodying my invention, with the cylinders in section; Fig. 2 is an enlarged sectional detail of one 60 end of the crank shaft and its associated pair of pistons, with some of the parts in section the better to show their relationship; Fig. 3 is a side elevation, on a still larger scale, showing the parts at the crank shaft, with 65 one pair of associated connecting rods and part of one piston and the operating mechanism for shifting the sun gear to vary the compression space; Figs. 4 to 7 inclusive are diagrams showing the different positions of 70 the piston in a pair of cylinders at ends of successive strokes throughout the four strokes of the cycle, with the sun gear remaining in fixed position; and Figs. 8 and 9 are similar diagrams showing the effect of 75 shifting the sun gear.

The crank shaft 10 for the four-cylinder engine shown is provided at its two ends with crank pins 11 and 12 respectively, which crank pins and shaft may be of any 80 desired construction, though as shown the crank pins are carried by fly wheels 13 and 14 fixed on the shaft 10 and suitably counterweighted at 15 (Fig. 2). The crank pins 11 and 12 are diametrically offset with respect to the crank shaft axis (Fig. 1), and each crank pin is associated with the connecting rods from the pistons of two diametrically opposed cylinders—17 and 18 for the crank pin 11, and 19 and 20 for the 90 crank pin 12. The connecting-rod mounting for each crank pin and its associated pair of cylinders is the same as that for the other, so that it will be necessary to describe only the connections at one crank pin, say 95 the crank pin 11.

On this crank pin 11 is rotatably mounted a sleeve formed of a gear 21, a middle eccentric portion 22, and two eccentric portions 23 located on opposite sides of the middle eccentric portion 22. The two eccentric portions 23 are exactly alike, with a common axis, and carry the forked crank-shaft end of the connecting rod 25 associated with the piston 27 in the cylinder 17. The middle eccentric portion 22 carries the crank-shaft end of the connecting rod 26 associated with the piston 28 in the cylinder 18. The crank-shaft end of the connecting rod 26 is thus located between the prongs of the 105 connecting rod 25, to equalize their action. The common axis A

of the two eccentrics 23 and the axis B of the eccentric 22 are offset from the axis C of the crank pin 11 by equal amounts, but in directions at right angles to each other, as is clear from Figs. 1 and 4 to 9 inclusive. 5 This right-angle relationship between the offsettings of the axes A and B is a fixed relationship, though the direction of such offsettings with relation to the crank pin 10 and the crank shaft varies in the operation of the engine and is also variable, under suitable control, to vary the compression space, as will hereinafter appear. As shown, this control is manual, and is obtained by 15 moving the gear 21, which is a planet gear, about its axis, which is the axis C.

The planet gear 21 is connected to a sun gear 30 which is co-axial with the crank shaft 10 but is normally fixed though circumferentially adjustable. This sun gear 30 does not rotate with the crank shaft. In order that the planet gear 21 may rotate in space at half crank-shaft speed, as is desired in the preferred form of my invention, such planet gear is twice the diameter of the sun gear 30, as is clear from Figs. 1, 2, and 3, and is connected to the sun gear through a pair of idler gears 31 carried by a shaft 32 mounted in the fly wheel 13, 25 the two idler gears of such shaft meshing respectively with the sun gear 30 and the planet gear 21, which are located on opposite sides of such fly wheel. In Fig. 2 the shaft 10 is partly broken away to show the 30 idler gear 31 beneath it. With this arrangement, the planet gear and the eccentric carried thereby rotate in space 180° about the axis C for every revolution of the crank shaft 10.

40 The sun gear 30 is adjustable circumferentially through a limited range, to vary the position of the axes A and B independently of the movement of the crank shaft 10. This adjustment of the sun gear 30 is obtained 45 in any desired way. As shown, such sun gear is fixed to a sleeve 35, from which projects an arm 36 carrying a gear segment 37, with which meshes a suitable pinion 38 movable, if desired through several rotations, 50 by an arm 39 telescopically extensible so that a pin 40 carried by the outer end thereof may be made to travel in a path fixed by partitions 41 on a fixed plate 42 and be brought into co-operation with and held by 55 any one of the holes 43 provided in such plate and arranged in two or more annular series interconnected by the grooves provided by the partitions 41.

With the sun gear 30 in about its middle 60 position of adjustment, in which position it is assumed to be in Figs. 1 to 7 inclusive, when the crank pin 11 is in the axial line of the two cylinders 17 and 18 and toward the cylinder 17, as indicated in Figs. 1, 2, 65 3, 4, and 6, the axis B of the eccentric 22

is offset from the axis C substantially in such axial line of the two cylinders, while the axis A of the eccentrics 23 is offset from the axis C at right angles to such axial line. With the crank pin 11 toward the cylinder 18, as indicated in Figs. 5 and 7, the offsetting of the axis A is in the axial line of the two cylinders, and that of the axis B is at right angles to such line. This offsetting of each respective axis A and B is in opposite directions from the axis C at the ends of alternate revolutions of the crank shaft, as indicated by a comparison of Figs. 4 and 6 or of Figs. 5 and 7. Thus as the engine operates, the eccentrics 22 and 23 as actuated 80 by the planet gear 21 rotate in space 90° while the crank shaft rotates 180° . This is indicated diagrammatically in Figs. 4 to 7 inclusive. In these figures, the piston 27 is shown in the positions it has at the ends 85 of the compression, power, exhaust, and intake strokes, respectively; while the piston 28 is shown in the positions it has at the ends of the power, exhaust, intake, and compression strokes, respectively. In other 90 words, for this pair of cylinders, the piston 28 is one quarter of a cycle ahead of the piston 27; while the pistons for the cylinders 19 and 20, which pistons are connected to the crank pin 12, are respectively one quarter and one half of a cycle 95 behind the piston 27. When the crank shaft makes one complete rotation, the eccentrics 22 and 23 are rotated 180° in space. Therefore, starting from a point where one of 100 the axes A and B is displaced along the axial line of the associated cylinder in one direction from the axis C, as the axis B is displaced to the right from the axis C in Fig. 4, after a rotation of the crank 105 shaft through 360° , or to the position shown in Fig. 6, the displacement of such eccentric axis is just opposite along the axial line of the cylinders from the axis C from what it was at the start; which means that 110 at the ends of the power and intake strokes the piston connected to that eccentric is in different longitudinal positions in its cylinder, the difference being equal to twice the distance by which the eccentric axis is offset from the axis C, so that at the end of the power stroke the piston uncovers a supplemental exhaust port 45 at the end of the intake stroke. On the other hand, starting from a point where the eccentric axis A or B is displaced from the axis C at right angles to the axial line of the associated cylinders, as the axis A is displaced 115 from the axis C in Fig. 4, after a rotation of the crank shaft through 360° , or to the position shown in Fig. 6, the displacement of such eccentric axis is merely on the opposite side of the axial line of the cylinders without any difference longitudinally of such axial line; which means that at the 120 125 130

ends of the compression and exhaust strokes the piston connected to that eccentric is in the same longitudinal position in its cylinder. This makes the power stroke of each 5 piston longer than the intake strokes.

As at the end of the compression stroke of a piston its associated eccentric axis (the axis A for the piston 27 in Fig. 4) is displaced from the axis C to one side of the 10 axial line of the cylinders, an adjustment of the sun gear 30 by the manipulation of the arm 39 shifts such eccentric axis around the axis C in the small circle D; but the arc of movement of the axis A is then nearly parallel to the axial line of the cylinders so that this results in a longitudinal movement of the piston 27 either to increase the size of 15 the compression space E as indicated in Fig. 8 for an adjustment of the sun gear 30 in one direction or to decrease the size of such compression space as indicated in Fig. 9 for 20 an adjustment of the sun gear in the other direction from the middle position which it is assumed to have in Figs. 1 to 7 inclusive. 25 Thus the size of the compression space is varied to suit different fuels. This adjustment of the sun gear does not greatly affect the piston position at the ends of the power and intake strokes, however, because of the 30 movement of the associated eccentric axis, say the axis B for the piston 28 in Figs. 4 and 6, is in parts of the circle D which are nearly at right angles to the axial line of the cylinders so that only a very small component of the movement of the axis B is 35 longitudinal of such axial line. In consequence, the position of the piston at the ends of the power and intake strokes is nearly the same longitudinally of the cylinders for 40 all positions of adjustment of the sun gear 30, as is clear from a comparison of the positions of the piston 28 in Figs. 4, 8, and 9.

In operation, as in all internal combustion engines, the use of a fuel which volatilizes 45 at low temperature facilitates starting, as is well recognized in internal combustion practice, and for this reason such a fuel is preferably used for starting. Such a fuel, however, operates first with rather low compression, in order to permit easy cranking or starting and to avoid pre-ignition, and so for starting with such a fuel the sun gear is 50 adjusted to give a large compression space E, as indicated in Fig. 8. The engine is set 55 into operation in the usual manner, and the several pistons go through their four-stroke cycles. Considering the piston 27, for instance: on its intake stroke it draws in a charge through the intake port 46, the intake stroke being of such length that the supplemental exhaust 45 in the cylinder wall is not uncovered; then on the compression stroke the charge thus drawn in is compressed to a point determined by the size of 60 65 the compression space E as set by the adjust-

ment of the sun gear 30; then the explosion is produced, and the piston is moved on its power stroke, which is longer than the intake stroke so that at the end of the power stroke the supplemental exhaust ports 45 in the cylinder wall are uncovered to permit the burned gases to escape while the main exhaust valve for the exhaust port 47 is still closed, so that it is possible by thus relieving the pressure in the cylinder before the end 70 of the power stroke to get the full expansion of the burning gases before allowing them to escape; and then, the main exhaust valve in the exhaust port 47 having been opened, which opening is easy because the 75 pressure on such exhaust valve has been relieved, the piston moves on its exhaust stroke to expel the remaining burned gases in the cylinder through the exhaust port 47, such 80 expulsion being with the burned gases under 85 greatly reduced pressure by reason of the earlier escape through the port 45, so that a more complete exhaustion of the burned gases is obtained. After the engine has been 90 in operation long enough to be suitably warmed, the fuel may be changed to one which volatilizes at a higher temperature, but which operates best at higher compressions, and so when the change of fuel is 95 made the sun gear 30 is adjusted to get the desired size of the compression space E, which may be as shown in Fig. 9. The general operation of the engine remains the same as before, save that the compression obtained is greater.

In the four-cylinder engine shown, with two pairs of opposed cylinders respectively at opposite ends of the crank shaft 10, the order of firing of the cylinders is 18—17—19—20. This produces a substantially balanced action. Each pair of cylinders has its own controlling sun gear 30, with the connections therefrom to the associated planet gear and eccentrics, and the two sun gears may be controlled either separately or 100 jointly as desired, though preferably jointly by a single controlling arm 39. The power from the crank shaft is conveniently taken off at an intermediate point, between the two pairs of cylinders, as by a central gear 105 110 fixed on such shaft.

I claim as my invention:

1. In an internal combustion engine, the combination of a cylinder, a piston movable therein, a crank shaft having a crank pin, 115 an eccentric mounted on said crank pin and adjustable around the axis thereof, means for rotating said eccentric in space about the crank pin axis at a different angular speed from that of the crank shaft and so 120 that it normally arrives at the same position at the end of each alternate revolution of the crank shaft, a connecting rod connecting said eccentric to said piston, and means for adjusting said eccentric about the axis of 125 130

- said crank pin while the engine is in operation to vary the position of the piston in the cylinder at the end of the compression stroke thereof.
5. 2. In an internal combustion engine, the combination of a cylinder, a piston movable in said cylinder, a crank shaft, an eccentric carried by said crank shaft, a connecting rod between said eccentric and said piston, 10 said eccentric being associated with said crank shaft so that during the rotation of the crank shaft it has a rotary movement about an axis eccentric to itself and eccentric to the crank shaft but rotatable with the 15 crank shaft, and gearing for producing such rotary movement of said eccentric at an angular velocity half that of the crank shaft, said gearing being manually operable independently of the crank-shaft movement.
20. 3. In an internal combustion engine, the combination of a cylinder, a piston movable in said cylinder, a crank shaft, an eccentric carried by said crank shaft, a connecting rod between said eccentric and said piston, 25 said eccentric being associated with said crank shaft so that it is adjustable about an axis eccentric to itself and to the crank shaft, means for adjusting said eccentric about such axis to vary the compression 30 space of said cylinder.
4. In an internal combustion engine, the combination of a cylinder, a piston movable therein, a crank shaft, a sleeve carried by said crank shaft and movable about an axis 35 eccentric to the crank shaft, a connecting rod connecting said piston to said sleeve and connected to said sleeve on an axis eccentric to the sleeve axis, a stationary adjustable member concentric with the crank shaft, 40 gearing between said stationary member and said sleeve to produce rotation of the latter about its axis at half the angular speed of the crank shaft, and means for adjusting said stationary member about its axis to vary the 45 position of said sleeve independently of the crank shaft movement.
5. In an internal combustion engine, the combination of a cylinder, a piston movable therein, a crank shaft, a sleeve carried by 50 said crank shaft and movable about an axis eccentric to the crank shaft, a connecting rod connecting said piston to said sleeve and connected to said sleeve on an axis eccentric to the sleeve axis, said sleeve having an ex- 55 ternal gear fixed thereto, a stationary external adjustable gear concentric with the crank shaft, said first-named gear being of twice the diameter of the second-named gear, idler gears carried by the crank shaft and 60 meshing with the first-named and second-named gears, and means for adjusting said stationary gear about its axis.
6. In an internal combustion engine, the combination of a cylinder, a piston movable 65 therein, a crank shaft having a crank pin, an eccentric mounted on said crank pin and adjustable around the axis thereof, means for rotating said eccentric in space about the crank pin axis at a different angular speed 70 from that of the crank shaft and so that it normally arrives at the same position at the end of each alternate revolution of the crank shaft, a connecting rod connecting said eccentric to said piston, and means for adjusting said eccentric about the axis of said 75 crank pin while the engine is in operation.
7. In an internal combustion engine, the combination of a cylinder, a piston movable in said cylinder, a crank shaft, an eccentric carried by said crank shaft, a connecting rod 80 between said eccentric and said piston, said eccentric being associated with said crank shaft so that during the rotation of the crank shaft it has a rotary movement about an axis eccentric to itself and eccentric to the 85 crank shaft but rotatable with the crank shaft, and gearing for producing such rotary movement of said eccentric at an angular velocity half that of the crank shaft, said gearing being manually operable independently 90 of the crank-shaft movement.
8. In an internal combustion engine, the combination of a cylinder, a piston movable therein, a crank shaft, a connecting rod connecting said crank shaft to said piston, and 95 gearing for varying the effective length of the crank arm on which said connecting rod is connected to said crank shaft periodically during the operation of the engine to produce a longer average effective length during 100 the power stroke than during the suction stroke.
9. In an internal combustion engine, the combination of a cylinder, a piston movable therein, a crank shaft, a connecting rod connecting said crank shaft to said piston, and gearing for varying the effective length of the crank arm on which said connecting rod is connected to said crank shaft in a cycle 105 requiring two revolutions of the crank shaft 110 for its completion, and producing a longer average effective length during the power stroke than during the suction stroke.
10. In an internal combustion engine, the combination of a cylinder, a piston movable 115 therein, a crank shaft, a connecting rod connecting said crank shaft to said piston, and gearing for varying the effective length of the crank arm on which said connecting rod is connected to said crank shaft at will to 120 vary the compression space of the cylinder, and also to vary such effective length periodically during the operation of the engine.
11. In an internal combustion engine, the 125 combination of two opposed cylinders, pistons movable therein, a crank shaft between said opposed cylinders, a sleeve carried by said crank shaft and movable about an axis eccentric to the crank shaft, two connecting 130

rods connecting the respective pistons to said sleeves and connected to said sleeves on axes which are offset from the sleeve axis at right angles to each other, and means for rotating 5 said sleeve about its axis.

12. In an internal combustion engine, the combination of two opposed cylinders, pistons movable therein, a crank shaft between said opposed cylinders, a sleeve carried by 10 said crank shaft and movable about an axis

eccentric to the crank shaft, two connecting rods connecting the respective pistons to said sleeves and connected to said sleeves on axes which are offset from the sleeve axis at right angles to each other, and means for rotating 15 said sleeve about its axis once for every two crank shaft revolutions to make alternate complete reciprocations of the two pistons of different length.

GRANVILLE G. WESTERFIELD.
